SWINGING FRAME BAND-SAWING
MACHINE

Joseph L. Ashworth, Worcester, Mass.

Application May 15, 1947, Serial No. 748,241

3 Claims. (Cl. 143—19)

1

This invention relates to sawing machines, and more particularly to that type of sawing machine which employs a power-driven endless saw-band.

It is a primary object of the present invention to provide a sawing machine of the type having a work-holding means and a continuously rotating saw-band with means whereby these two latter elements may be adjusted relative to each other so that the work or stock may be cut at various predetermined angles.

Another primary object of the present invention is to provide a sawing machine having a power-driven endless saw-band with a pivoted saw-carrying frame which is designed in a manner such that it will afford a maximum amount of unobstructed working space about the area of the work.

A further object of the present invention is to provide a machine of the above described type which is adapted to operate in a highly efficient manner but which at the same time is so designed that it may be inexpensively manufactured.

With the above and other objects in view, as will hereinafter appear, the invention comprises the devices, combinations and arrangements of parts described in connection with the accompanying drawings which illustrate a preferred embodiment of the invention in which:

Fig. 1 represents a perspective view of a machine in which the present invention is incorporated.

Fig. 2 represents, on an enlarged scale, a right-hand end view of the machine illustrated in Fig. 1.

Fig. 3 represents, on a scale similar to that used in Fig. 1, a top plan view, partly in section, of the present machine taken substantially along line 3—3 of Fig. 2, but with the arm 34 rotated through an angle A.

Fig. 4 represents, on a scale similar to that used in Fig. 1, a view of the saw-band carrying frame as viewed along the line 4—4 of Fig. 2.

Fig. 5 represents, on an enlarged scale, a vertical sectional view of the present machine taken substantially along line 5—5 of Fig. 3.

Referring particularly to Figs. 1 and 5 of the drawings, the present sawing machine comprises a main support base which includes a hollow column or pedestal 10 supported in a vertical position by means of a plurality of horizontally disposed feet 11, 11 which are welded, or otherwise suitably secured, as at 12, to the column 10. Welded, or otherwise suitably secured, within the top portion of the column member 10 is a cap or

2

disk 13 to which a substantially horizontally disposed T-shaped anvil or work-supporting member 14 is secured by means of a plurality of bolts 14a.

As may be best seen from Figs. 3 and 5, the anvil member 14 is formed with a substantially horizontally disposed work-supporting surface 15 upon which is adapted to be secured a stationary work-holding jaw 16. Bolts 17, 17 are adapted to secure the stationary jaw 16 directly upon the surface 15 of the anvil member 14. This jaw 16 is provided with the usual type of vertically disposed work-engaging surface 18, and cooperating with the jaw 16 is a movable jaw 19 which is also supported upon the surface 15 of the anvil 14. The anvil is also provided with a longitudinally disposed slot 20 formed in the surface 15 thereof. Slidably mounted within this slot is a tongue portion 21 of a block 22 which is disposed beneath the surface 15 of the anvil member 14. One or more bolts 23, 23 are adapted for securing the movable jaw 19 to the block 22 in a fashion such that the jaw and block may be shifted as a unit longitudinally of the slot 20.

Projecting from the left-hand end of the anvil member 14 (see Fig. 3) is a hollow tube 24 in which is suitably rotatably mounted a shaft 25 one end portion of which is threaded into the guide block 22. The other end portion of the shaft 25 has a hand wheel 26 provided thereon so that an operator may adjust the jaw 19 towards and away from the jaw 16 by merely turning the handle 26 in either a clockwise or a counterclockwise direction. Suitable means, not herein disclosed, are associated with the shaft 25 for preventing the axial movement of the same within the tube 24. From the above it is to be understood that stock may be readily placed upon the mid portion of the horizontally disposed anvil surface 15 and thereafter the movable jaw 19 may be shifted toward the stationary jaw 16 to the end that the work will be suitably clamped in a proper position.

Still referring to Figs. 3 and 5, there is projecting from the forward portion of the anvil 14 a guide cylinder 27 which is slidably received within a hollow collar 28 suitably secured upon the forward portion of the anvil member 14. This cylinder 27 may be shifted back and forth within the collar 28 and, furthermore, may be locked in any desired position by merely tightening a set screw 29 which is threaded radially within the collar 28. Slidably mounted upon the distal end of the cylinder 27 is a second collar 30 upon which is pivotally mounted a gauge bar

31. A set screw 32 is threaded radially within the collar 30 for clamping the latter in any desired position longitudinally of the cylinder 27. From the above it is to be understood that the bar 31 may be used as a work-gauge to the end that the work may be properly positioned initially between the jaws 16 and 19.

Referring now to Fig. 5, the upper portion of the column member 10 is reduced in diameter as at 33 and is adapted to receive thereabout a hollow sleeve portion 34' of a pivoted arm 34 which extends horizontally, as shown in Fig. 3. The lower portion of the sleeve 34' rests upon a plurality of bearing balls 35, 35 which are disposed circumferentially about a shoulder 36 formed at the junction between the reduced portion of the column 10 and the lower or main section thereof. An annular ball-retaining gib 37 is suitably positioned about the column 10 so as to retain the balls 35, 35 in position. From the above it is to be understood that the pivoted arm 34 is mounted in a fashion such that it may be freely rotated about the column 10 upon the anti-friction balls 35, 35. Referring particularly to Fig. 1, the sleeve 34' is provided with a longitudinal slot 38 which permits the sleeve to be clamped tightly about the column 10 for the purpose of locking the sleeve in any desired position of angular adjustment. For the purpose of so locking this sleeve the latter element is provided with a pair of projecting bosses 39 and 40 of which the latter is threaded to receive a clamping screw 41. A portion of the screw passes freely through the boss 39 and bears against the same so that the screw may, in the usual manner, function to tighten the sleeve 34' about the column 10.

As may be best seen in Figs. 1, 2 and 3, the pivot arm 34 extends outwardly from the column 10 to form a mounting upon which a saw-band frame may be pivotally mounted. More specifically, there is pivotally mounted within the extreme end portion of the arm 34 a rock shaft 42 the opposite end portions of which extend beyond the confines of bearing bosses 43 and 44 provided upon the opposite sides of the arm 34. Supported directly upon the opposite end portions of the rock shaft 42 are a pair of vertically disposed side members 45 and 46 which, at their upper portions, have connected thereto a saw-carrying frame 47. Suitable nuts 48 and 49 are each threaded over a respective end portion of the rock shaft 42 for the purpose of clamping the side members 45 and 46 in a proper position. From the above it is to be understood that the frame member 47 is supported entirely upon the rock shaft 42 and, furthermore, through the medium of this rock shaft, the frame 47 with its component parts, is adapted to be rocked relative to the stationary support base and in a vertical plane.

Disposed about one end portion of the rock shaft 42, at a point between the bearing boss 43 and the side frame element 45, is a torsion spring 50 one end portion 51 of which is secured to the side frame member 45 while the other end portion 52 thereof is secured to a head member 53 which in turn is pivotally mounted upon the top portion of a hand screw 54. This hand screw 54 is threaded within a bracket 55 provided upon the pivot arm 34. Thus, by adjusting the hand screw 54 in a vertical direction one may alter the effective force of the torsion spring 50 to the end that the frame unit 47 may be properly counterbalanced about the rock shaft 42. A

chain 56 is provided on the present machine for preventing the frame 47 from swinging in an upward direction beyond a safe predetermined angle. As may be best seen in Fig. 1, the upper portion of this chain 56 is secured directly to a portion of the frame 47, while the lower portion of the chain is secured directly to the upper surface of the pivot arm 34. In order to prevent the frame 47 from swinging downwardly toward the anvil member beyond a predetermined point, there is provided a stop in the form of a bar 57 which is secured between the two side members 45 and 46. As may be best understood by referring to Figs. 1 and 2, this bar 57 is provided with a pair of adjustable stop screws 58, 58 which are threaded through the bar so as to engage the upper surface of the arm 34 and thereby prevent the frame from moving downwardly beyond a predetermined angle.

20 The above noted saw-carrying frame 47 comprises a pair of laterally spaced and parallel platform members 59 and 60, which have their upper surfaces disposed in a common plane which in turn is disposed normally at a 45° angle with the horizontal. The platform members 59 and 60 are joined together at their rear and normally elevated edge portions by means of a bridge-piece 61 and at their forward and normally depressed edge portions by means of an inverted U-shaped yoke arm or guide 62. Thus, the platforms 59 and 60 normally straddle both jaw members 16 and 19 in a fashion such that a maximum amount of clear work area is provided thereabout.

Referring particularly to Figs. 2 and 3, the upper portion of the side frame member 46 extends upwardly beyond the confines of the platform member 60 thereby to form a lip member 63. An electric motor, generally designated by 40 the numeral 64, is carried upon a base member 65 the lower portion of which is adapted to be pivotally secured upon the back side of the side frame member 46 as at 66. The upper portion of this base 65 is biased away from the side frame 46 by means of a coil spring 67 surrounding a bolt 68 which passes through both the side frame member 46 and the platform 65. A nut 69 holds the bolt in place and prevents the platform 65 from shifting away from member 46 beyond a predetermined angle.

55 The motor 64 is provided with the usual rotary shaft 70 upon which is mounted a grooved pulley 71. A V-belt 72 is trained over the pulley 71 and also over a second grooved pulley 73 which is carried upon the distal end of a shaft 74 which in turn is suitably journaled within a gear box 75 best shown in Figs. 1 and 4. This gear box 75 is suitably formed on the platform member 60. Also suitably mounted within the 60 gear box 75 is a pulley shaft 76 which is adapted to be driven by the shaft 74 through the medium of a worm 77 and wheel 78, respectively mounted upon the shafts 74 and 76. From the above it should be understood by those skilled in the art 65 that the pivotal mounting 66 functions to permit the motor 64 to pivot thereabout for the purpose of maintaining the belt 72 at a proper tension at all times.

70 Mounted upon the cross shaft 76 is a saw-band wheel 78 which is disposed in a plane parallel to the platform member 60 and which is adapted to receive and power an endless saw-band 79 which is also trained over a second wheel 80. Referring particularly to Fig. 4, the wheel 80 is 75 rotatably mounted upon a block 81 which is en-

gaged by an adjusting screw 82. Suitable means, not herein shown, are provided for guiding the block 81 so that as the adjusting screw 82 is rotated about its longitudinal axis the block 81 and the wheel 80 will move toward and away from the saw wheel 78 to the end that the saw 79 will be maintained at a proper tension. The screw 82 is suitably journaled within a block 83 mounted upon the platform member 59, and a handle member 84 is secured upon one end of the screw for the purpose of providing means whereby an operator may adjust the second saw wheel 80 in a manner as hereinabove described. A cover plate 85 is adapted to be removably secured over the adjusting block 81 by means of a plurality of screws 86, 86 which are threaded directly into the platform member 59. Thus, from the above, it is to be understood that the motor 64 is adapted to drive the shaft 74 which in turn, through the medium of the reduction gears 77 and 78, functions to rotate the saw-band 79 in a continuous direction past the work held between the jaws 16 and 19.

Referring particularly to Figs. 1 and 2, it is to be understood that the guide yoke 62 is disposed in a vertical plane and it is provided with a pair of depending guide arms 87 and 88 the upper portion of each of which is formed as an open jaw unit which is adapted partially to encircle the horizontal portion of the yoke 62. Also, each of the jaw portions of the arms 87 and 88 is provided with a hand screw 90 which functions to clamp the arm in any desired position longitudinally of the yoke 62. The lower portion of each of the arms 87 and 88 is formed as a guide for the purpose of receiving the working portion of the saw band 79. It is the function of each of these guides 91 and 92 to deflect the working portion of the saw band from its normal path so that it will be disposed in a vertical plane. From this it is to be understood that the guides 87 and 88 may be adjusted back and forth relative to each other, depending upon the width of the work to be sawed, so that the working portion of the saw band will be held in a vertical plane thereby effectively to operate upon the work or stock. It should be obvious that the distance between the guides 87 and 88 should be reduced in the event that work of small width is to be sawed for the reason that it is always desirable to keep the length of the working portion of saw-band at a minimum.

As hereinabove described, the frame member 47 carries the entire saw-operating mechanism in a unitary manner and this entire unit is pivotally carried upon the rock shaft 42 so that the arm 34 will be effective to adjust the entire frame and saw band operating mechanism about the vertical axis of the column 10 whenever the arm is suitably rotated upon its bearing means. From this it is to be understood that the saw will be effective to sever the work at any desired angle relative to the longitudinal axis thereof. In other words, once the work is clamped between the jaws 16 and 19, the frame unit 47 may be properly adjusted relative to these jaws and about the longitudinal axis of the column 10 so as to sever the work at any desired angle. Prior to inserting work between the jaws 16 and 19 the frame unit 47 is swung upwardly thereby to give the operator proper clearance, and thereafter the frame is swung towards the work and the weight of the frame is sufficient to enable the saw to cut the work in a proper manner. However, as hereinabove described, the effective downward force of

the frame 47 may be varied by means of the hand screw 54 which functions to increase or decrease the force of the torsion spring 50. From this it should be understood that the novel design of the frame unit 47, with its spaced-apart platform members 59 and 60, affords a maximum amount of unobstructed working space about the work-clamping jaws 16 and 19, and the fact that the motor 64 is mounted upon the frame 47 makes for a machine which is most compact and free from any protruding and ungainly power-connecting elements between the frame and base.

I claim:

1. A sawing machine comprising, a vertically disposed base column, a substantially horizontally disposed work-support carried upon the top portion of said column, a sleeve rotatably mounted in surrounding relation about said column just beneath said work-support, an arm carried by and projecting radially from said sleeve, a frame unit pivotally mounted about a horizontal axis and upon the free end portion of said arm so as to be movable toward and away from said work-support, said frame including a pair of parallel and substantially laterally spaced saw-carrying platforms normally disposed so as to straddle said work-holding means and having the planes defined thereby inclined relative to the horizontal, a bridge member securing the normally elevated rear edge portions of said platforms together, a substantially inverted U-shaped yoke member disposed in a vertical plane and having the spaced-apart lower leg portions thereof securing the normally depressed forward edge portions of said platforms together, an endless saw-band rotatably supported by each of said platforms with the plane defined by said saw-band being disposed in parallel relation with said two platforms, a pair of guide arms adjustably mounted upon and depending downwardly from the top portion of said yoke for guiding the working portion of said saw-band in a vertical plane at all times, and an electric motor carried upon said frame for driving said saw-band.
2. A sawing machine comprising, a vertically disposed base column, a substantially horizontally disposed work-support carried upon the top portion of said column, a sleeve rotatably mounted in surrounding relation about said column just beneath said work-support, an arm carried by and projecting radially from said sleeve, a frame unit including a pair of parallel and substantially laterally spaced saw-carrying platforms normally disposed so as to straddle said work-holding means and having the planes defined thereby inclined relative to the horizontal, a bridge member securing the normally elevated rear edge portions of said platforms together, a pair of flat vertically disposed parallel frame-support members pivotally mounted at their lower ends about a horizontal shaft carried by the free end of said arm, the upper end portions of said two frame-support members each being rigidly secured to a respective one of the upper and lower sides of one of said platforms thereby pivotally to support said frame upon said arm, an endless saw-band rotatably supported by each of said platforms with the plane defined by said saw-band being disposed in parallel relation with said two platforms, a substantially inverted U-shaped yoke member disposed in a vertical plane and having the spaced-apart lower leg portions thereof securing the normally depressed forward edge portions of said platforms together, a pair of guide arms adjustably mounted upon

and depending downwardly from the top portion of said yoke for guiding the working portion of said saw-band in a vertical plane at all times, and an electric motor mounted upon that frame-support member which is secured to the upper side of one of said platforms, said motor being connected with said saw-band for driving the same.

3. A sawing machine comprising, a vertically disposed base column, a horizontally disposed work-support mounted upon the top of said column, a sleeve rotatably mounted on said column beneath said work-support, an arm carried by and extending radially from said sleeve, a saw frame pivotally mounted about a horizontal axis upon the free end of said arm, so as to be movable toward and away from said work-support, said frame including a pair of parallel, laterally spaced platforms normally disposed so as to straddle said work-support, with the common plane of said platforms inclined from the horizontal, a bridge member securing said platforms together and providing a portion extending horizontally above said work-support, an endless saw-band extending around the edge

of said frame and supported by wheels mounted in said platforms, an electric motor carried by said frame for driving said saw-band, and arms extending downwardly from the horizontal portion of said bridge member for guiding said saw-band in a vertical plane.
